UNITED STATES PATENT OFFICE.

OTTO G. FABER, OF WASHINGTON, DISTRICT OF COLUMBIA.

SAFETY ATTACHMENT FOR WATCHES, &c.

SPECIFICATION forming part of Letters Patent No. 339,870, dated April 13, 1886.

Application filed February 1, 1886. Serial No. 190,560. (No model.)

To all whom it may concern:

Be it known that I, OTTO G. FABER, of Washington city, in the District of Columbia, have invented a new and useful Improvement 5 in Safety Attachments, of which the following is a description.

My invention is an improved safety attachment for use in connection with watches, to prevent the same from being dropped out of 10 or stolen from the pocket; and the invention consists in certain novel constructions and combinations of parts, as will be described.

In the drawings, Figure 1 is a sectional view of a pocket provided with my improvements. 15 Fig. 2 is a partial back view of same. Fig. 3 is a side view of my improvement, showing how the chain-swivel is applied to the supporting-bail. Fig. 4 is a longitudinal section, enlarged, of the chain-swivel; and Figs. 5 and 20 6 are detail views.

The pocket is provided with the supporting-bail A, which has the ends of its arms 1 perforated at 2, and provided slightly in advance of such perforations with stop-shoulders 3. In applying this supporting-bail its 25 perforated arms are forced from within the pocket through the rear wall thereof, and thence through perforations 4 in the back plate, B, which is arranged, as shown, against 30 the outer side of the rear wall of the pocket. To secure the supporting-bail, a fastening-staple, C, is arranged in rear of the pocket, and has the ends of its arms 3 passed through 35 the perforations 2 in arms 1 of the bail. This fastening-staple in turn is held by a button, 5, pivoted to the back plate, so it may be turned over the cross-bar of the staple to secure it, or away from said cross-bar to permit 40 the staple to be removed, as will be understood from the dotted lines in Fig. 2.

The chain-swivel D, except in the features presently described, may be of the spring-tongue variety, or of the common form having a threaded collar, by which it may be fastened. 45 It is preferred, however, to use the spring-tongue variety, as shown. The swivel is provided, usually on its rear side, with a hook, E, which, for convenience of reference, I term the "supplemental" hook, for the reason it 50 performs an additional purpose from that effected by the swivel proper. A latch, F, is

secured to the swivel, and has its end or point arranged to bear upon and close the hook E.

In the construction shown the latch is pivoted to the body of the swivel at 6, and bears 55 at its point upon the hook, being spring-actuated, in order to hold its point normally on the hook in order to close the same. It will be understood, however, that the latch might be formed of spring metal, secured rigidly to 60 the body of the swivel, and bearing at its point by its own tension upon the hook. This would involve no departure from the broad principles of my invention; but I prefer the construction shown and before described. I 65 also prefer to rest the point of the latch on and extend it beyond the hook, the extension at 7 serving to guide the hook into proper engagement with the supporting-bail in the use of the device. By preference I also pivot 70 the latch between its ends, forming an extension in rear of its pivot, by which the latch may be easily operated to release the swivel from the supporting-bail.

The body of the swivel is socketed to receive the spring G, which bears at one end 75 against the latch, and at its other end against the pivoted tongue of the swivel. By this arrangement a single spring serves to give tension to each of said parts. This spring is 80 usually supported by a spring, 8, bearing between it and the base of the socket in the swivel. In operation, as the watch is dropped into the pocket, the point of latch F bears over the cross-bar of the bail, and the latter 85 slips into engagement with the hook, and when it is desired to remove the watch the wearer can conveniently release the latch.

Manifestly the swivel, constructed substantially as described, might be sold separately, 90 and used by the purchaser in connection with any suitable form of loop or supporting-bail; but the construction of bail and its fastening devices, as shown, are preferred, for the reason they avoid any stitching or sewing of metallic 95 devices to the pocket and facilitate the connection of such parts, as will be manifest from the drawings and foregoing description.

Having thus described my invention, what I claim as new is—

1. A safety attachment consisting of a watch-chain swivel having its body or main

portion adapted to secure a watch-ring, and having such body formed with a supplemental hook, and provided with a latch adapted to close said supplemental hook, substantially as set forth.

2. A safety attachment comprising, in combination, the chain-swivel having a ring for connection with the chain, a body or main portion by which to secure the watch-ring, and having its body formed with a supplemental hook, and a spring-actuated latch connected with said body and arranged to close the supplemental hook, substantially as set forth.

3. In a safety attachment, a chain-swivel having a supplemental hook and provided with a latch pivoted between its ends, forming a rear or handle extension and a point extension, the latter being rested upon and extended in advance of said hook, and a spring engaging said latch.

4. In a safety attachment, and as an im-

proved article of manufacture, a chain-swivel having a pivoted tongue and a supplemental hook, and provided with a pivoted latch arranged to close said hook, and a spring engaging at opposite ends with the said latch and tongue, substantially as set forth.

5. In a safety attachment, the combination of the chain-swivel having a supplemental hook and a latch for closing the same, the back plate having perforations, the supporting-bail having the ends of its arms perforated and provided with stop-shoulders, the fastening-staple having its arms passed through the perforations in the supporting-bail, and a latch arranged to engage and lock said staple, substantially as set forth.

OTTO G. FABER.
